FLOATING DRY DOCK

Frederic R. Harris, New York, N. Y.

Application January 6, 1942, Serial No. 425,736

8 Claims. (Cl. 114—45)

1

This invention relates to floating dry docks.

One object of the invention is to provide a design of building that simplifies the construction so that the dock can be put together with less skilful labor than has heretofore been required.

Another object of the invention is to provide an improved dry dock construction which is less expensive to build, and which is especially suitable for composite docks, constructed partly of steel and partly of timber. The invention effects a substantial saving in the fastenings required to construct the dock, and fastenings are an important item in the total cost of a dry dock.

In accordance with one feature of the invention, timber truss posts are clamped between steel bottom and deck stringers and end grain timber compression is directly transferred into the tension truss members through contact plates that simplify the construction and protect the stringers that constitute the truss chord section proper. Timbers have a corrosive effect on steel in the presence of moisture because of acid in the wood. With this invention the contact plates or saddles used over the ends of the timber posts are made heavy enough so that they are still of ample strength even if they suffer some corrosion, and I-beams of standard design are used as stringers, the flanges of the I-beams being fully protected by the saddles. This invention provides a dry dock construction that is both simple and practical, and composite constructions have the advantage that the steel acts as ballast for the wood when the dock is submerged. In the conventional timber dock, the ballast amounts to as much as 28% of the lifting capacity of the dock, and is a considerable item of cost.

The composite dock can therefore be of smaller size than a timber dock of the same ship capacity and this reduces the dredging required for the dock slip.

In accordance with one feature of the invention parts of the dock, such as bulkheads, are constructed remote from the place of assembly of the dock, to eliminate carpenter fitting during the assembly of the structure, and to reduce the length of time that the dock requires the use of the launching ways and equipment. This means that more sections of docks can be built in a given length of time with the same number of launching ways, or that fewer launching ways and less equipment are required to build the same number of docks. By the expression "remote from the place of assembly" is meant some location other than the launching ways on which

2

the dock is put together and then slid into the water.

Other objects, features and advantages of the invention will appear or be pointed out as the specification proceeds.

In the accompanying drawing, forming a part hereof:

Fig. 1 is an end view of a complete dock made in accordance with this invention.

Fig. 2 is an enlarged, transverse, sectional view through one side of the dry dock shown in Fig. 1.

Fig. 3 is an enlarged sectional view of the line 3—3 of Fig. 2.

Fig. 4 is an enlarged sectional view taken on the line 4—4 of Fig. 3, looking from left to right.

Fig. 1 shows a floating dry dock with a pontoon 11 and side walls 12. The pontoon 11 has a round bottom 13, and has a deck 14 with an arcuate crown. Tapered sections can be used in place of the round ones. Blocks 15 are shown on the deck 14. The end of the pontoon is indicated by the reference character 16.

Within the pontoon there are deck stringers 17 which are structural steel I-beams; and bottom stringers 18 which also are structural steel I-beams. These stringers necessarily include a number of beam sections connected together, as by field welds 19, in the case of a wide dry dock, and the stringers extend from one side 20 to the other side of the pontoon.

The dock includes a central longitudinal bulkhead 21 which is water-tight, and a number of swash bulkheads 22, 23 and 24 at spaced regions transversely of the pontoon. Each of the bulkheads 21—24 extends the full length of the pontoon and helps to provide longitudinal rigidity for the dry dock.

The longitudinal bulkheads 21—24 each include planking 25 that passes between reinforcements 40 such as upright reinforcement timbers 27 at both sides of the bulkhead. The deck stringers 17 are located directly above the bottom stringers 18 and there are timbers 27 between the deck and bottom stringers at the different stations lengthwise 45 of the pontoon as indicated in Fig. 3. At several places along the length of the pontoon there is a transverse water-tight bulkhead 29 located between successive deck and bottom stringers and one of which is shown in Fig. 3.

The transverse bulkheads 29 include planking 30 located between uprights 31 that are held in place by wooden members 32 which extend to the next stringer 17 or 18.

The end 16 of the pontoon is shown in section 55 in Fig. 3. End planking is fastened to upright

timbers 34 that are on opposite sides of each of the longitudinal bulkheads 21-24 and similar to the upright timbers 27 except for greater length. There is a wooden deck stringer 35 across the upper ends of the timbers 34, and a wooden bottom stringer 36 across the lower end of these timbers 34. The planking of the deck 14 is fastened to the stringer 35, and the planking of the bottom 13 to the stringer 36.

The deck planking and bottom planking are fastened to the I-beam stringers 17 and 18, respectively, by bolts, preferably carriage bolts 39. Contact plates or saddles 40 are connected to the bottom flanges of the deck stringers 17 and to the top flanges of the bottom stringers 18 by welding. Welds 41 are indicated in Figs. 3 and 4. There is one of these saddles 40 in position to contact with the top and bottom of each of the longitudinal bulkheads 21-24. These saddles 40 are not connected to the longitudinal bulkheads, but slope downward on either side of the bulkheads, and the upright timbers 27 are cut away at their corners to fit into the saddle as shown in Fig. 4.

There is a fabric lining 43 coated with some protecting substance, for example, canvas painted with red lead, between the top of each of the timbers 27 and the under side of the saddle 40. Each end portion of the saddle 40 extends into a yoke 45 and is connected with the yoke by a pin 46. The yoke is welded to a rod 47.

The rod 47 from the saddle 40 at the upper end of the bulkhead 23 (Fig. 2) extends downward in the direction of the lower end of the next bulkhead 22 and is joined by a turnbuckle 48 with a rod 49 extending upward from the yoke 45 that connects with one end of the saddle 40 at the lower end of the bulkhead 22. The yokes 45, rods 49 and turnbuckle 48 constitute a diagonal tension member 50 that holds the bulkhead in position. There are similar diagonal tension members or braces 50 extending from both sides and from both the top and bottom of each of the bulkheads 21-24, but two tension members are used for the diagonal braces that slope downward toward the right in Fig. 2 and only one tension member for the diagonal bracing that slopes upward toward the right. Such a construction obtains a centralized tension even though it is impossible for the braces from opposite directions both to be on the center line of the truss. The saddles 40 have openings for two pins 46 in one end portion and for a single central pin opening in the other end portion.

The method of constructing the dry dock is as follows:

The center bulkhead 21, the swash bulkheads 22-24, and similar swash bulkheads for the other half of the pontoon; the sections for the transverse bulkheads 29, and the ends 16 of the pontoon, are constructed flat on the ground, each of these elements of the dock being made up into separate units remote from the place of assembly of the dock.

The bottom stringers 18 are then located in spaced relation, the distance between them being determined by spacing strakes 52. The longitudinal bulkheads 21-24 are placed in their proper upright positions on top of the bottom stringers 18. The transverse bulkheads 29 are then secured in position. There may be two or more of these transverse bulkheads along the entire length of the pontoon, and each transverse bulkhead is made in sections that fit between the successive longitudinal bulkheads 21-24. The

pontoon ends are also hoisted in place and fastened in position.

The deck stringers are then laid across the longitudinal bulkheads and properly spaced by top spacing strakes 53. There are brackets 54 welded to the flanges of the stringers 17 and 18. These brackets are T-sections and disposed with the stem of each T vertical. Intermediate vertical timbers 55 are clamped between the brackets 54, these timbers having slotted ends into which the stems of the brackets extend. In this invention all of the upright timbers are held in place without the use of fastening elements penetrating or passing through them. The tension members 50 are put in place and the turnbuckles 48 are tightened up to give the transverse truss structure the desired rigidity.

The frames of the wing walls 12 are assembled flat on the ground and then hoisted into place and clamped to the truss ends. The bottom and deck planking 13, 14 is then bolted to the flanges of the stringers 18 and 17, respectively, by bolts 39. The side planking of the pontoon and wings is spiked to the uprights of the frames of the wings 12. The wing deck 55 is then put on and the dock is ready for launching.

The invention eliminates carpenter fitting in the assembly of the dock as all parts are pre-cut, and the deck and bottom planks are drilled in 30 a jig for exact bolt fit. The dock of this invention can be assembled in less than half the time of a conventional dock, thus affording corresponding economy of launching ways and equipment.

The preferred embodiment of the invention has been described, but changes and modifications can be made and some features of the invention used without others.

I claim:

40. 1. A dry dock pontoon including a transverse truss structure that comprises a deck stringer, a bottom stringer, upright timbers between said stringers at spaced positions along the length of the stringers, said timbers having their grain 45 extending upright, saddles in contact with the end grain of the upper and lower end faces of the upright timbers and extending along a part of the length of the upright timbers, said saddles compressing the upright timbers between them, and diagonally extending tension members connecting the upper and lower saddles of successive upright timbers for imparting rigidity to the truss.

55. 2. A floating dry dock comprising a pontoon including a number of spaced apart bulkheads extending lengthwise of the pontoon, each bulkhead including longitudinally-extending planking and vertical timbers in pairs on opposite sides of the planking at spaced positions along the length of the bulkhead, a metal saddle extending across the upper ends of each pair of said timbers, another metal saddle extending under the lower ends of each pair of said timbers, each of said saddles having end portions that extend at an acute angle to the sides of the vertical timbers, each of said saddles having a corrosion-resisting material in contact with the timber, tension members extending from the end portions of the upper saddles to the end portions of the lower saddles of the next bulkhead on each side, turnbuckles in the tension members for adjusting the tension of said members, a metal deck stringer welded to the corresponding upper saddles of the respective bulkheads, and a metal

bottom stringer welded to the corresponding lower saddles of the respective bulkheads.

3. A floating dry dock comprising a pontoon including a number of spaced apart bulkheads extending lengthwise of the pontoon, each bulkhead including longitudinally-extending planking and vertical timbers positioned in pairs on opposite sides of the planking at spaced positions along the length of the bulkhead, a metal saddle extending across the upper ends of each pair of said timbers, another metal saddle extending under the lower ends of each pair of said timbers, each of said saddles having end portions that extend at an acute angle to the sides of the vertical timbers, each of said saddles having a corrosion-resisting material in contact with the timber, braces extending from the end portions of the upper saddles to the end portions of the lower saddles of the next bulkhead on each side, a metal deck stringer welded to the corresponding upper saddles of the respective bulkheads, and a metal bottom stringer welded to the corresponding lower saddles of the respective bulkheads.

4. A floating dry dock comprising a pontoon including a number of spaced apart bulkheads extending lengthwise of the pontoon, each bulkhead including longitudinally-extending planking and vertical timbers positioned in pairs on opposite sides of the planking at spaced positions along the length of the bulkhead, a metal saddle extending across the upper ends of each pair of said timbers, another metal saddle extending under the lower ends of each pair of said timbers, each of said saddles having end portions that extend at an acute angle to the sides of the vertical timbers, tension members extending from the end portions of the upper saddles to the end portions of the lower saddles of the next bulkhead on each side, turnbuckles in the tension members for adjusting the tension of said members, a metal deck stringer welded to the corresponding upper saddles of the respective bulkheads, and a metal bottom stringer welded to the corresponding lower saddles of the respective bulkheads.

5. A floating dry dock comprising a pontoon including a number of spaced apart bulkheads extending lengthwise of the pontoon, each bulkhead including longitudinally-extending planking and vertical timbers in pairs on opposite sides of the planking at spaced positions along the length of the bulkhead, a metal saddle extending across the upper ends of each pair of said timbers, another metal saddle extending under the lower ends of each pair of said timbers, each of said saddles having end portions that extend at an acute angle to the sides of the vertical timbers, braces extending from the end portions of the upper saddles to the end portions of the lower saddles of the next bulkhead on each side,

a metal deck stringer welded to the corresponding upper saddles of the respective bulkheads, and a metal bottom stringer welded to the corresponding lower saddles of the respective bulkheads.

6. A floating dry dock pontoon including longitudinally extending bulkheads spaced from one another transversely of the pontoon, and deck stringers above the bulkheads, a saddle connected with the lower side of each deck stringer above each bulkhead and contacting with the top of the bulkhead over the full width thereof, said saddle extending part way down on opposite sides of the bulkhead, corresponding saddles connected with the upper side of each bottom stringer below each bulkhead and contacting with the bottom of the bulkhead over the full width of the bottom, and means clamping the saddles firmly against the tops and bottoms of the bulkheads.

20 7. A floating dry dock having parallel bulkheads and an additional bulkhead intersecting same, spaced upright reinforcements on both faces of said parallel bulkheads adjacent the places of intersection, plates on the ends of said

25 reinforcements and diagonal braces connecting the ends of said plates of one bulkhead with the ends of the plates of the next parallel bulkhead.

8. A composite steel and wood dry dock pontoon including bulkheads, a steel deck stringer extending across the upper ends of the bulkheads, a steel bottom stringer extending across the lower ends of the bulkheads, timber uprights located between the bulkheads and extending from the deck stringer to the bottom stringer with the end grain of said timber uprights compressed between the steel stringers, brackets connected to the stringers, stems extending from the brackets, and recesses in the end faces of the uprights into which the stems of the brackets extend.
